UNITED STATES PATENT OFFICE.

LINNAEUS T. CANFIELD, OF TOLEDO, OHIO.

DENTAL INSTRUMENT.

1,187,497.

Specification of Letters Patent. Patented June 20, 1916.

Application filed March 10, 1916. Serial No. 33,224.

To all whom it may concern:

Be it known that I, LINNAEUS T. CANFIELD, a citizen of the United States, residing at Toledo, in the county of Lucas and 5 State of Ohio, have invented certain new and useful Improvements in Dental Instruments; and I do declare the following to be a full, clear, and exact description of the invention, such as will enable others, skilled 10 in the art to which it appertains to make and use the same, reference being had to the accompanying drawings, and to the letters and figures of reference marked thereon, which form a part of this specification.

15 In the practice of dentistry, the delicate operations of removing nerves and of exploring and treating nerve-canals are rendered difficult for the operator, as well as painful to the patient, owing to the many 20 different positions which such an instrument must assume, and to the irregular and oftentimes obscure course of the channel to be followed.

25 My invention relates to an instrument designed to largely obviate the difficulties here indicated, and, more particularly, is designed to provide an instrument which, while furnishing a rigid shaft, providing an ample handle for the firm hold of the 30 operator's fingers, is still so delicately flexible near its forward end as to yield to the slightest change of position of the handle or to the course of the pliant broach removably held at the extreme end of the instrument in 35 the grip of a suitable chuck.

To these ends, my device consists of the construction and arrangement of parts hereinafter described, and shown, and illustrated in the accompanying drawings, in which— 40 Figure 1, is a side-elevation of my instrument in normal position; Fig. 2, the same, showing the connection between the handle and the chuck hereinafter referred to, flexed, the dotted lines indicating, approximately, the range of the instrument's deflection, and Fig. 3, an enlarged view, in central longitudinal section, of my device.

Like numerals of reference indicate like views throughout the drawings.

50 In the drawings, 1 is a stem or handle,

preferably corrugated longitudinally, to afford a holding surface for the fingers of the operator.

2 is a closely coiled fine wire helix, the 55 opening at one end of which receives and is secured upon the reduced portion 3 of the handle 1. The other end of the helix receives and is secured upon the inner end of a chuck 4, which may be of any suitable construction. In the present instance, for illustration, the chuck consists of a cylindrical piece of steel 5, split lengthwise into four equal segments, the splits extending from the blunt point formed by its conical end to 60 near the encircling helix, thus forming prongs 6. The conical quadripartite nose of the cleft piece 5 is threaded to receive the nut 7. The prongs 6 are resilient. The butt of the broach 8, which is usually of about the 65 diameter of a fine sewing needle, being inserted into the socket between the ends of the prongs 6, and the nut 7 being set up, the ends of the prongs are compressed inwardly and the end of the broach is tightly 70 clamped in operative relation to the handle. Now the turning of the handle will cause a like turning of the broach. It will be seen that owing to the flexibility of the connection between the handle and the 75 broach, as well as to the flexibility of the broach itself, the broach may be effectively turned and manipulated throughout an arc of nearly one hundred and eighty degrees. The operator is thus enabled to reach with 80 ease the root or nerve canal of every tooth 85 in the mouth.

Another advantage of the construction here described is that since the short resilient helix shown forms the sole connection between the handle and the chuck, the helix while capable of holding the chuck and handle normally in alinement not only permits the deflection above described but being slightly extensible and compressible, serves 90 as a delicate cushion against the longitudinal 95 movements and pressures of the broach.

I am aware that flexible shafts consisting, in part, of coiled wire are not new, and I do not, therefore, claim a flexible connection in a rotatable shaft, but 100

What I claim and desire to secure by Letters Patent, is—

A dental instrument comprising, in combination, a handle, a chuck having compressible arms adapted to clamp a broach, a compression-nut for compressing said arms, and a wire helix forming sockets at each end for receiving the opposed ends of the chuck and

the handle, said helix forming the sole connection between the handle and the chuck. 10

In testimony whereof I affix my signature in presence of two witnesses.

LINNAEUS T. CANFIELD.
